UNITED STATES PATENT OFFICE.

ERASTUS E. WINKLEY, OF LYNN, MASSACHUSETTS.

AUTOMATIC SHOE-MACHINE.

1,088,390.

Specification of Letters Patent. Patented Feb. 24, 1914.

Application filed July 27, 1910. Serial No. 574,062.

To all whom it may concern:

Be it known that I, ERASTUS E. WINKLEY, a citizen of the United States, residing at Lynn, in the county of Essex and State of Massachusetts, have invented certain new and useful Improvements in Automatic Shoe-Machines; and I do hereby declare the following to be a full, clear, and exact description of the invention, such as will enable other skilled in the art to which it app pertains to make and use the same.

The present invention relates to machines for operating upon boots and shoes in which the shoe and operating means are relatively movable to transfer the point of operation of the operating means around the shoe, and in which the relative movements between the shoe and means for operating thereon are automatically controlled and effected so that the shoe is automatically presented to the operating means as the point of operation is transferred around the shoe.

The object of the invention is to provide novel and improved means for automatically correcting the relative position of the shoe and operating means to maintain them in proper relation at the point of operation as this point progresses along the shoe, whereby the operation of the machine is rendered more uniformly certain and reliable.

To these ends the invention contemplates utilizing some predetermined contour or contours of the shoe to control and determine the corrective movements requisite for maintaining the operating means and shoe in proper relation. By these means the relative movements imparted to the shoe and operating means are made to depend upon the contour of the shoe being operated upon, so that each shoe is properly presented to the operating means, notwithstanding unavoidable variations in shape which occur in different shoes, even when of the same style and size. This also enables shoes of different size and style to be operated upon without change or adjustment in the correcting mechanism. The contour of the shoe which may be utilized to the best advantage to control the corrective movements will depend upon the character of the machine in which the invention is to be em-

bodied, and upon the operation which it is to perform upon the shoe. It will usually be desirable to utilize as the controlling contour a shoulder or abutment extending along or adjacent to the margin of the shoe sole, or to utilize the surface close to such a shoulder or abutment.

The broader features of the invention may be embodied in machines for performing various operations which are customarily performed upon partially completed shoes, and may be embodied in mechanisms for effecting any desired corrective movements between the shoe and operating means.

In the specific embodiment of the invention shown in the drawings the invention is embodied in a machine for sewing the inseam of welt or turn shoes, and is utilized to relatively swing the shoe and sewing mechanism to maintain the channel forming the inner surface of the between-substance parallel to the line of feed, the corrective swinging movements being imparted to a jack upon which the lasted shoe is supported. In this construction the bottom of the channel is the contour on the shoe which controls and determines the swinging movements which are imparted to the jack to maintain the shoe in proper position against the channel guide during the feed of the shoe. These swinging movements are determined by a feeler which acts along the bottom of the channel and causes the jack to be swung in accordance with the longitudinal curvature of the channel at the point where the sewing mechanism is acting on the shoe. Each shoe is therefore manipulated by the correcting mechanism in accordance with the contour of the channel in the sole of that particular shoe to keep the bottom of the channel at the sewing point substantially in line with the line of the feed of the shoe.

The various features of the invention will be readily understood from an inspection of the accompanying drawings and the following detailed description of the mechanism illustrated therein.

In the drawings Figure 1 is a side elevation of an inseam sewing machine embody-

ing the features of the invention in the forms in which it is preferred to employ when utilizing the invention to relatively swing the shoe and sewing mechanism; Fig. 5 is a side elevation showing the jack swinging mechanism on a larger scale than Fig. 1; Fig. 3 is a plan view of the mechanism shown in Fig. 2; Fig. 4 is a sectional elevation on line 4—4, Fig. 3; Fig. 5 is a sectional plan view on line 5—5, Fig. 2; Fig. 6 is a detail sectional view showing the clutch through which swinging movements are imparted to the jack; Fig. 7 is a sectional view on line 7—7, Fig. 6; Fig. 8 is a detail elevation showing the feeler for engaging the channel in the shoe sole; Fig. 9 is a front elevation looking toward the left in Fig. 8; Fig. 10 is a detail plan view of the auxiliary feeding mechanism, and of the devices for constraining the jack to swing about the point of operation of the sewing mechanism; Fig. 11 is a sectional elevation on line 11—11, Fig. 10; Fig. 12 is a sectional plan view on line 12—12, Fig. 11; and Fig. 13 is a vertical sectional view on line 13—13, Fig. 10.

In the machine shown in the drawings the means for operating upon the shoe consists of a sewing mechanism which is similar in construction to the construction of the well-known Goodyear welt and turn sewing machine shown and described in Patent No. 412,704, October 8, 1889. The shoes to be operated upon are carried upon a freely movable jack, and correcting mechanism is provided for properly swinging the jack to maintain the bottom of the channel adjacent to the point of operation of the sewing mechanism parallel with the direction of feed. The sewing mechanism is mounted upon a support 1, and is provided with a channel guide 2, a back-gage 3, a feeding awl 4, and the usual coöperating stitch forming devices. The shoe to be operated upon is carried upon a jack which is provided with heel and toe supports 5 and 6 for supporting a lasted shoe. The jack is secured upon the upper end of a sleeve 7 which surrounds a shaft 8 mounted in the outer end of a supporting arm 9. The sleeve is free to slide vertically upon the shaft, and is connected to turn with the shaft by means of a yoke 10 secured to the upper end of the shaft, and having one of its arms 55 slotted to embrace one of the arms 11 of the jack. The rear end of the supporting arm 9 is mounted to turn freely about a shaft 12 which is mounted in bearings in the outer end of a second arm 13, the rear end of which is in turn mounted to turn freely upon a shaft 14 mounted in the frame of the machine. These supporting devices permit the jack to be moved freely in any direction in presenting a shoe to the sewing mechanism and in manipulating it dur-

ing the feed of the shoe. The jack is forced yieldingly toward the sewing mechanism by a spring 15 connected to one end of a bell crank lever 16, the other end of which engages a collar 17 on the sleeve 7.

The feeding awl of the sewing mechanism acts in the usual manner to feed the shoe, and the shoe is swung to properly guide it during the feed by imparting turning movements to the shaft 8. The turning movements requisite for properly swinging the shoe during the sewing of the seam are imparted to the shaft 8 through chains 18 and 19 passing about sprocket wheels 20, 21 and 22 secured to the lower end of the shafts 8, 12 and 14 respectively.

The swinging movements are imparted to the shoe when the needle is in engagement with the work, and the shoe will therefore be swung about the point of operation of the sewing mechanism. In order that the shoe may be properly guided, the mechanism for swinging the shoe is so controlled by the contour of the channel that the shoe is swung in accordance with the longitudinal curvature of the channel at the point of operation of the sewing mechanism to maintain the bottom of the channel in line with the feed. The devices for thus swinging the shoe comprise a feeler 23 arranged to engage the bottom or base of the channel substantially the distance of one stitch length in advance of the needle, and connected to control the mechanism which imparts turning movements to the jack turning shaft 8. The feeler 23 is in the form of a finger pivoted to the lower end of the carrier lever 24, which is pivoted upon the end of an overhanging arm 25. The feeler finger 23 is forced yieldingly toward the surface of the sole of the shoe by a spring 26 the compression of which may be adjusted by an adjusting screw 27 (Fig. 8). The feeler carrying lever 24 is connected through a link 28 with a second lever 29, which is in turn connected through a link 30 with a lug 31 projecting from a pulley 32. The feeler is forced toward the base of the channel by a spring 33. The pulley 32 is connected to turn in unison with a second pulley 34 through a wire belt 35 which passes about the pulleys and about guide pulleys 36, and may be tightened to take up all slack and lost motion by a turn buckle 37. The pulley 34 is provided with a radially projecting arm 38 which is connected by a link 39 with one end of a sliding bar 40, the other end of which is connected by a link 41 with one arm of a bell crank lever 42 (Fig. 2). The other end of the bell crank lever carries a roll engaging a cam 42' secured to a cam shaft 48, and acting to intermittently withdraw the feeler finger from engagement with the base of the channel, for a purpose to be explained. The

- bell crank lever 42 carries a roll 43, the position of which is controlled by the feeler 23 through the connections between the feeler and roll carrying lever 42. The position 5 of the roll 43 when the feeler is in engagement with the base of the channel will depend upon the position of this point in the channel with relation to the point in the channel where the stitch is being formed.
- 10 The position of the roll determines the extent and direction of the turning movement which is imparted to the jack turning shaft 8 to bring the point in the channel engaged by the feeler into the line of feed.
- 15 The mechanism through which the roll determines the rotary movement imparted to the shaft 8, comprises a reciprocating controller plate 44 provided at its upper end with two oppositely inclined surfaces 20 45 adapted to pass on opposite sides of the roll 43 when the roll is in mid or neutral position. The plate 44 is pivotally mounted upon one end of a reciprocating carrier lever 46, the other end of which carries a 25 roll engaging a cam 47 which is secured to a continuously rotating cam shaft 48. The cam shaft 48 makes one revolution for each revolution of the cam shaft of the sewing mechanism, so that the controller plate 44 30 is advanced and retracted during each cycle of operations of the sewing mechanism. The lower end of the controller plate 44 is connected through a link 49 with an arm 50 projecting through a sleeve 51 which is 35 loosely mounted upon a shaft 52. A second arm 53 projects from the sleeve 51, and is connected by a link 54 with an arm or link 55. The rear end of the link 55 is pivoted to a pivot block 56 mounted to slide in a 40 segmental slot formed in an actuator lever 57. The actuator lever is pivotally supported in a bearing 58 (Figs. 3 and 5), and the segmental slot in which the pivot block 56 is mounted extends on opposite sides of 45 the pivot of the lever. The lower end of the actuator lever carries a roll which is held in engagement with a cam 59 on the cam shaft 48 by a spring 60. The actuator lever is thus reciprocated during each cycle 50 of operations of the sewing mechanism. The other end of the link 55 is pivotally connected to a sliding bar 61, the end of which is connected by a link 62 with one arm of a clutch operating lever 63. The other end 55 of the lever is provided with a gear segment 64 which engages a pinion 65 formed on the hub of the member 66 of a clutch from which turning movements are imparted to the jack turning shaft 8. The jack turning 60 clutch is a double-acting Horton clutch, the driven member of which consists of a disk 67 secured to a hollow shaft 68 (Fig. 6). This shaft carries a sprocket wheel 69 which is connected by a chain 70 with a 65 sprocket wheel 71. The sprocket wheel 71 is connected with a gear 72 engaging a gear 73 connected with the sprocket wheel 22 through which turning movements are transmitted to the shaft 8. The rolls 74 of the clutch are forced in a direction to wedge 70 between the flange 75 of the driving member 66 and the clutch surfaces 76 on the driven member 67 by spring-pressed pins 77, and are forced back to render the clutch inactive by bell crank levers 78. The bell 75 crank levers are forced in a direction to release the clutch pawls by a spring 79, and are actuated to render the clutch inactive through a rod 80 extending through the hollow shaft 68 and engaging the ends of the 80 levers. The rod is actuated at proper intervals by a cam 81 on the cam shaft 48 which engages one end of a lever 82, the other end of which is connected with the upper end of the rod 80.
- 85
- So long as the point in the channel which is engaged by the feeler 23 is in the line of feed, the roll 43 will be positioned in mid or neutral position, when the feeler engages the channel. When the roll is in this position the inclined surfaces 45 on the controller plate 44 will pass on opposite sides of the roll without effecting any swinging movement of the plate. The connections between the plate and the pivot block 56 90 are such that under these conditions the pivotal connection between the block and link 55 will be in line with the axis of the actuating lever 57. No turning movement will therefore be imparted to the jack 95 swinging clutch so long as the base of the channel remains in the line of feed. Whenever the point of the channel engaged by the feeler is out of the line of feed, the roll 43 will be positioned either to the 100 right or left of the neutral position a distance proportional to the position of the point in the channel engaged by the feeler with relation to the line of feed. Now when the controller plate 44 is raised, one 110 of the surfaces 45 will ride against the roll and swing the plate about its pivot. This movement of the plate will through the connections described shift the pivot block 56 to one side or the other of the axis of the 115 actuating lever 57, so that during the active stroke of the lever the driving member 66 of the jack swinging clutch will operate to swing the jack and shoe through the distance requisite for bringing the point of 120 the channel engaged by the feeler in to the line of feed. As soon as the roll 43 has been positioned by the feeler, it is locked and held during the advance movement of the controller plate by a clamp 83 arranged 125 to engage the sliding bar 40. This clamp is carried in one arm of a bell crank lever 84, the other arm of which carries a roll engaging an operating cam 85 secured to the cam shaft 48. As soon as the controller plate 130

44 has been advanced and has positioned the pivot block 56, the block is locked in position, and the controller plate is retracted to free the roll 43, the clamp 83 being also released so that the feeler finger 5 may be immediately withdrawn from the channel, and so that the roll 43 may be again positioned by the feeler. The pivot block is thus locked by a clamp 86 arranged 10 to engage a segment 87 secured to the sleeve 51. The clamp 86 is carried in one arm of a bell crank lever 88, the other arm of which carries a roll engaging a cam 89 on the cam shaft 48. A weight 90 is connected 15 with the sleeve 51 to counterbalance the weight of the parts connected with the sliding pivot block 56. The controller plate 44 and pivot block are returned to neutral position after each cycle of operations by a 20 cam plate 91 provided with a V-shaped mouth arranged to engage a roll on the controller plate. A spring 92 is connected with the link 49, and tends to retract the controller plate.

25 The parts are shown in the position which they occupy after the shoe feeding movement of the feeding awl and channel guide has just been completed. The feeler has engaged the base of the channel and positioned the 30 roll 43, the controller plate 44 is retracted, the pivot block 56 and the jack swinging clutch are in neutral position, and the actuating lever is in its retracted position. Starting with the parts in this position, the 35 cycle of operations performed during each cycle of operations of the sewing mechanism is as follows: The roll 43 is locked in position by the clamp 83, and then the controller plate 44 is raised and by its engagement with the roll 43, positions the pivot block 56 on the actuator lever 57. The clamp 86 immediately locks the pivot block in this position, and then the lever 46 which carries the controller plate is released by its cam, so 40 that the controller plate may partially return to neutral position, thus freeing the roll 43. These movements take place while the needle of the sewing mechanism is advancing through the work, and before the 45 awl and channel guide have returned to their initial position. The bell crank lever 42 is then actuated by its cam to retract the feeler so that the feeding awl and channel guide may be retracted preparatory to the 50 next feed, and the channel guide may engage the channel at substantially the point which was engaged by the feeler. During the return movement of the awl and channel guide, the actuating lever 57 is rocked by its 55 cam to operate the driving member 66 of the jack swinging clutch, so that the swinging movement of the shoe takes place while the needle is still in the stock. During the feed of the shoe the jack swinging clutch is disengaged, and the actuating lever is returned 60

to retracted position, the clamp 86 being released so that the plate 44 may be returned to its retracted position. As the feed of the shoe is completed, and the awl and channel guide are disengaged from the channel, the 70 cam 42' releases the bell crank lever 42, so that the feeler is again advanced and engages the channel, preparatory to the next cycle of operations. Thus during each cycle of operations the feeler engages the channel 75 at a point in advance of the needle substantially equal to each feeding movement of the shoe and sets the jack swinging mechanism, so that this point in the channel is swung into the line of feed where it will be properly engaged by the channel guide and awl. 80

In sewing shoes having substantially flat soles, the shoe may be maintained in proper relation to the sewing mechanism by the swinging movements imparted to the shoe. 85 To insure the proper engagement of the channel guide with the base of the channel in sewing shoes the soles of which have a moderate longitudinal curvature, it may be found desirable to mount the channel guide 90 and awl upon the feed slide in such manner that they may move vertically to accommodate themselves to the vertical position of the surface of the sole, and to provide centering levers 93 and cams 94 for bringing 95 the channel guide and awl into proper vertical relation to the needle previous to the passage of the needle through the stock, as is more fully explained in Patent No. 1,030,- 043, June 18, 1912. 100

In order to relieve the needle or other device of the sewing mechanism from the strain to which they would otherwise be subjected during the swinging of the jack, additional devices are provided for constraining 105 the jack to swing about the point of operation of the sewing devices. In the construction shown these devices consist of a clamp, the jaws 95 and 96 of which are arranged to grip a plate 97. The plate 97 is secured to 110 the yoke 10 so that it turns with the jack and has an outline corresponding generally to the shape of a shoe sole, so that the marginal portion of the plate may travel between the jaws of the gripper as the jack is moved 115 longitudinally and swung during the sewing operation. The jaws of the clamp are so arranged that a line passing through the point of operation of the sewing mechanism, and parallel with the axis of the jack turning shaft 8, will pass through the axis of 120 the jaws. When the clamp is engaged with the plate, therefore, it will form a pivot about which the jack will swing when the jack turning shaft is rotated, and as this 125 pivot is in line with the point of operation of the sewing mechanism, the clamp will constrain the jack to swing about the point of operation, and will relieve the strain to which the needle would otherwise be sub- 130

jected. The jaws of the pivot clamp are provided with studs 98 for engaging the opposite sides of the plate, and these studs are so mounted that they may turn freely in the 5 jaws of the gripper as the jack and plate 97 swing. The movable gripper jaw 96 is actuated to intermittently engage the gripper with the plate 97 by a cam 99 arranged to engage a lever 100 which is pivoted on the 10 gripper jaw and transmits a gripping pressure to the jaw through a spring similar to the spring 101 shown in Fig. 13.

In order to assist the awl in feeding the shoe, or to relieve it of the strain incident 15 to overcoming the inertia and friction of the jack supporting devices, a supplemental feeding mechanism is provided for imparting feeding movements to the jack in unison with the feeding movements of the awl. 20 As shown, the supplemental feeding devices consist of a feeding gripper arranged to act on the plate 97. The feeding gripper comprises an arm 102 pivotally mounted in a bracket 103, and provided at its forward end 25 with a freely turning stud 104 for engaging the under side of the plate 97. The movable jaw 105 of the feeding gripper is pivoted on the plate 102, and is provided with a pivoted gripping stud 106 at its forward end. The 30 jaw 105 is actuated to intermittently grip the plate 97 by a cam 107 arranged to engage the end of a lever 108 which is pivoted on the jaw 105 and imparts a clamping pressure to the jaw through the spring 101 above 35 referred to. The feeding gripper is actuated to impart feeding movements to the plate 97 and connected jack through an arm 109 which projects from the hub of the arm 102 and is connected by a link 110 with one 40 arm of a bell crank lever 111. The other arm of the bell crank lever carries a roll which is held in engagement with a cam 112 by a spring 113. The link 110 is adjustably connected to the arm of the bell crank lever 45 111, so that the feeding movement of the gripper may be adjusted to correspond to the feeding movement imparted to the shoe by the feeding awl. In order that the operator may disengage both the feeding and 50 pivot grippers from the plate, in case either of them are gripping the plate when it is desired to swing the jack out of position, the movable jaws 96 and 105 are extended rearwardly into position to be engaged by a cam 55 114 formed on the upper end of a stud 115. This cam is provided with an operating handle 116 through which it may be turned to depress the rear ends of the movable gripper jaws and thus disengage the front ends 60 of the jaws from the plate 97.

The cams for actuating the pivot and feeding grippers are secured on a shaft 117 which is continuously driven and makes one revolution for each revolution of the cam 65 shaft of the sewing mechanism. The cam

99 is so timed that the pivot gripper is engaged with the plate 97 when the correcting mechanism is operated to swing the jack, and is disengaged from the plate at other times. The cams 107 and 112 are so timed 70 that the feeding gripper engages and feeds the forward plate during the feeding movement of the awl, and is disengaged from the plate and returned to initial position during the return of the feeding awl.

The various mechanisms of the machine are driven from a main driving shaft 118 through a suitable form of clutch which is under the control of the operator. The driving shaft is connected through a chain 80 119 with a shaft 120. The cam shaft 121 of the sewing mechanism is driven from the shaft 120 through beveled gearing and a shaft 122. The cam shaft 117 is driven from the shaft 120 through the chains 123, 124 and 85 125, and the cam shaft 48 for the correcting mechanism is driven through the chains 123 and 126, the connections being such that the cam shafts 48 and 117 each make one revolution for each revolution of the cam 90 shaft 121.

While the invention has been illustrated and explained in connection with its application to mechanism for swinging the shoe during the operation thereon of inseam sewing mechanism, and certain features of the invention relate more particularly to such a machine and mechanism, it will be understood that the broader features of the invention may be embodied in machines for performing other operations upon a shoe, or in mechanisms for otherwise correcting the relative position of the shoe and means for operating thereon during the transfer of the point of operation of the operating means around the shoe to maintain the shoe and operating means in proper relation. It will also be understood that the specific construction and arrangement of the parts is not material to the broader features of the invention, and may be varied and modified to suit the type of machine in which the invention is embodied, and the character of the corrective movements which are to be effected, without departing from the invention. 105 110 115

Having explained the nature and object of the invention, and specifically described one form of machine in which it may be embodied, what I claim is:

1. An automatic shoe machine, having, in combination, means for operating on a shoe including devices for feeding the shoe by engagement therewith, a shoe supporting jack, and mechanism controlled by a contour of the shoe for relatively moving the jack and operating means to maintain them in proper relation as the point of operation of the operating means is transferred around the shoe, substantially as described. 120 125 130

2. An automatic shoe machine, having, in combination, means for operating on a shoe, devices for supporting and presenting a shoe to the operating means, feeding mechanism acting directly on the shoe, a feeler engaging the shoe in advance of the point of operation of the operating means, and mechanism controlled by the feeler for changing the relative position of the shoe and operating means and coöperating with the feed to present the shoe properly to the operating means as its point of operation is transferred around the shoe, substantially as described. 65
- 5 10 15 20 25 30 35 40 45 50 55 60
3. An automatic shoe machine, having, in combination, means for operating on a shoe and a shoe supporting jack relatively movable to transfer the point of operation of the operating means around the shoe, feeding mechanism acting directly on the shoe, a feeler engaging the shoe in advance of the point of operation of the operating means, and mechanism controlled by the feeler for relatively swinging the operating means and jack to maintain the edge of the sole in proximity to the operating means parallel to the line of feed, substantially as described. 70
4. An automatic shoe machine, having, in combination, means for operating on a shoe and a shoe supporting jack longitudinally movable and rotatable to transfer the point of operation around the shoe, and means controlled but not operated by a contour of the shoe for correcting the relative position of the shoe and operating means as the point of operation is transferred around the shoe, substantially as described. 75
5. An automatic shoe machine, having, in combination, means for operating on a shoe and a shoe supporting jack relatively movable to transfer the point of operation around the shoe, a feeler engaging the shoe, and mechanism controlled by the feeler for swinging the jack about the point of operation of the operating means to correct the position of the shoe with relation to the operating means as the point of operation is transferred around the shoe, substantially as described. 80
6. An automatic shoe machine, having, in combination, means for operating on a shoe including feeding and guiding devices, a feeler arranged to act along a contour of the shoe, and mechanism controlled by the feeler for relatively swinging the operating means and shoe to maintain it in proper relation to the guiding devices as the point of operation is transferred around the shoe, substantially as described. 85
7. An automatic shoe machine, having, in combination, means for operating on a shoe and a shoe supporting jack freely movable to transfer the point of operation around the shoe, and mechanism controlled by a con- 90
- tour on the shoe for swinging the jack about the point of operation of the operating means as said point is transferred around the shoe, substantially as described. 95
8. An automatic shoe machine, having, in combination, means for operating on a shoe including devices for feeding the shoe by engagement therewith, and mechanism controlled by a contour of the shoe for swinging the shoe in accordance with said contour, substantially as described. 100
9. An automatic shoe machine, having, in combination, means for operating on a shoe including devices for feeding the shoe by engagement therewith, a feeler acting along a contour of the shoe, and mechanism controlled by the feeler for swinging the shoe in accordance with the contour, substantially as described. 105
10. An automatic shoe machine, having, in combination, means for operating on a shoe and a shoe supporting jack relatively movable to transfer the point of operation of the operating means around the shoe, a feeler engaging the shoe along the path of travel of the operating means, mechanism acting at regular intervals during the operation of the operating means for changing the relative position of the operating means and jack, and devices connected with the feeler for determining the actuating movements of said mechanism, substantially as described. 110
11. An automatic shoe machine, having, in combination, means for operating on a shoe and a shoe supporting jack relatively movable to transfer the point of operation around the shoe, a feeler engaging the shoe along the path of operation of the operating means, mechanism operating at regular intervals for swinging the jack, and devices connected with the feeler for determining each jack swinging movement of said mechanism, substantially as described. 115
12. An automatic shoe machine, having, in combination, means for operating on a shoe including intermittently acting feeding devices, a shoe supporting jack, a feeler engaging the shoe at a point in advance of the operating means substantially equal to each feeding movement of the shoe, and a jack swinging mechanism controlled by the feeler to swing this point into the line of feed, substantially as described. 120
13. A sewing machine, having, in combination, mechanism for sewing the inseam of a lasted shoe, a feeler acting along the channel of the shoe and positioned thereby, and mechanism controlled by the feeler for swinging the shoe in accordance with the curvature of the channel during the operation of the sewing mechanism, substantially as described. 125
14. A sewing machine, having, in combi-

- nation, mechanism for sewing the inseam of a lasted shoe, a feeler acting along the channel of the shoe and positioned thereby, and mechanism controlled by the feeler for relatively moving the sewing mechanism and shoe, to maintain them in proper relation during the operation of the sewing mechanism, substantially as described.
15. A sewing machine, having, in combination, a sewing mechanism including shoe feeding devices, devices for supporting and presenting a shoe to the sewing mechanism, and mechanism controlled but not operated by a contour on the shoe for relatively moving the shoe and sewing mechanism about the point of operation to maintain them in proper relation during the operation of the sewing mechanism upon the shoe, substantially as described.
- 20 16. A sewing machine, having, in combination, a sewing mechanism including shoe feeding devices, devices for supporting and presenting the shoe to the sewing mechanism, and mechanism controlled by a contour on the shoe for swinging the shoe in accordance with the curvature of the contour to properly guide the shoe as it is fed by the sewing mechanism, substantially as described.
- 25 17. A sewing machine, having, in combination, mechanism for sewing the inseam of a lasted shoe including a channel guide, devices for supporting the shoe and presenting it to the sewing mechanism, and mechanism controlled by the contour of the channel for swinging the shoe in accordance with said contour to maintain the channel guide in the channel during the operation of the sewing mechanism on the shoe, substantially as described.
- 30 18. A sewing machine, having, in combination, mechanism for sewing the inseam of a lasted shoe, mechanism for swinging the shoe, and a feeler acting along the channel and connected to determine the movements imparted to the shoe by the swinging mechanism, substantially as described.
- 35 19. A sewing machine, having, in combination, mechanism for sewing the inseam of a lasted shoe, a feeler arranged to engage the channel in advance of the needle of the sewing mechanism, mechanism operating during each cycle of operations of the sewing mechanism for swinging the shoe, and devices connected with the feeler for determining the shoe swinging movements of said mechanism, substantially as described.
- 40 20. A sewing machine, having, in combination, mechanism for sewing the inseam of a lasted shoe, a feeler arranged to engage the channel substantially a stitch length in advance of the needle of the sewing mechanism, mechanism for advancing and retracting the feeler during each cycle of opera-
- tions of the sewing mechanism, mechanism operating during each cycle of the sewing mechanism for swinging the shoe, and devices connected with the feeler for determining the shoe swinging movements of said mechanism, substantially as described.
- 45 21. A sewing machine, having, in combination, a sewing mechanism, a shoe supporting jack, intermittently acting jack swinging mechanism, a feeler arranged to engage the channel at a point in advance of the needle of the sewing mechanism substantially equal to each feeding movement of the shoe and connected to set the jack swinging mechanism so that this point is swung into the line of feed at each operation of the jack swinging mechanism, substantially as described.
- 50 22. An automatic shoe machine, having, in combination, means for operating on a shoe, a shoe supporting jack movable to transfer the point of operation of the operating means around the shoe, mechanism acting independently of the feeding movements of the jack for imparting swinging movements to the jack, a plate connected to move with the jack, devices for gripping the plate to determine the point about which the jack swings, and a cam for intermittently engaging the gripping devices with the plate, substantially as described.
- 55 23. An automatic shoe machine, having, in combination, means for operating on a shoe, a shoe supporting jack movable to transfer the point of operation of the operating means around the shoe, mechanism acting independently of the feeding movements of the jack for imparting swinging movements to the jack, a plate connected to move with the jack, a pivot clamp arranged in line with the point of operation of the operating means, and a cam for operating the clamp to intermittently grip the plate, substantially as described.
- 60 24. An automatic shoe machine, having, in combination, means for operating on a shoe, feeding means acting on the shoe, a shoe supporting jack movable to transfer the point of operation of the operating means around the shoe, mechanism acting automatically to correct the relative position of the operating means and jack, supplemental feeding devices, and cams and connections for imparting feeding movements to the supplemental feeding devices corresponding to the feeding movements imparted to the shoe by the feeding devices engaging therewith, substantially as described.
- 65 25. An automatic shoe machine, having, in combination, means for operating on a shoe, a shoe supporting jack movable to transfer the point of operation around the shoe, mechanism acting automatically and

independently of the feeding movements of the jack to swing the jack to correct the relative position of the jack and operating means, a plate connected to move with the jack, a gripper for engaging the plate, and cams for actuating the gripper to intermittently grip the plate and impart feeding

movements to the jack, substantially as described.
